APPARATUS FOR APPLYING CAN LEADS
 Seymour Wilens, Wantagh, Martin Sievers, West Islip,
 and Lothar Achatz, Babylon, N.Y., assignors to The
 Staver Company Incorporated, Bay Shore, N.Y., a cor-
 poration of New York

Filed Apr. 26, 1966, Ser. No. 545,433
 13 Claims. (Cl. 29—203)

This invention relates to the manufacture of cans for electronic components, and more particularly to a machine for applying wire leads to the cans.

Electronic components are frequently housed in cans. For example, a tantalum capacitor may be housed in a drawn metal can having a diameter of say one-eighth inch and a length of say three-eighth inch, and the can may have a short wire lead secured thereto. It could be soldered or welded, but in the present case one end of the lead is staked in a hole in the bottom of the can.

The general object of the present invention is to provide an improved machine for applying the leads to the cans. A more particular object is to provide a machine which is simplified and relatively inexpensive, and yet which is efficient and fully automatic in operation.

To accomplish the foregoing general objects, and other specific objects which will hereinafter appear, my invention resides in the apparatus elements and their relation one to another, as are hereinafter more particularly described in the following specification. The specification is accompanied by drawings in which:

FIG. 1 is a plan view of a machine embodying features of the present invention, with the wire feed device and the can hopper omitted;

FIG. 2 is a vertical section taken approximately on the line 2—2 of FIG. 1;

FIG. 3 is a transverse section taken approximately on the line 3—3 of FIG. 2;

FIG. 4 is a vertical section taken approximately on the line 4—4 of FIG. 1;

FIG. 5 is a transverse section taken on the line 5—5 of FIG. 4;

FIG. 6 is a vertical section taken approximately on the line 6—6 of FIG. 1;

FIG. 7 is an enlarged vertical section corresponding to the right end of FIG. 4 and including a portion of one side of the wire clamp split die;

FIG. 8 is an enlarged schematic section showing how a can is fed to the headed end of a lead wire;

FIG. 8A is a similar schematic view showing the parts after staking the lead wire to the can;

FIG. 9 is an elevation showing the cam for moving the split die from station to station;

FIG. 10 is an elevation showing the cam for operating the heading punch;

FIG. 11 is an elevation showing the cam for operating the staking punch;

FIG. 12 is a perspective schematic view showing the apparatus with the wire feed and can hopper accessories; and

FIG. 13 shows the can delivery chute at the staking punch.

Referring to the drawing and more particularly to FIG. 8, the can 12 is a drawn sheet metal can, made typically of brass. It is quite small, having a dimension of say one-eighth inch in diameter and three-eighth inch long. It has a hole 14 in the center of the bottom to receive one end of a lead wire 16. The present machine severs the lead wire 16 from a continuous wire, and preliminarily upsets or heads the same as is indicated at 18. FIG. 8A shows how the end of the lead wire next is riveted or staked against the bottom of the can at 20, thereby securely attaching the parts together, with the can bottom

tightly held between the head 18 and the staked end 20.

Referring now to FIG. 12, the continuous wire 16' is fed from a reel 22 by an appropriate wire feed means 24. This may be a commercially available feed means, for example that made by Mechanical Tool and Engineering Company of Rockford, Illinois, and sold under the name "Rapid-Air." It preferably has accurate control or adjustment of the feed distance.

The cans are loaded into a bowl or hopper 26 which is supported on a vibratory base which in turn is elevated on a suitable column 26'. The hopper 26 aligns the cans and feeds them downward end-to-end through a plastic tube 27 to an orienting device 28 which may be conventional and which ensures that all of the cans are fed with their closed end foremost. The cans then continue their descent through a plastic tube 29 to the staking station of the machine. The hopper mechanism 26 may be a commercially available product, such as the Parts Feeder VFC #5 made by Vibratory Feeder Co. of Erie, Pa., which is a division of Automatic Devices, Inc.

Referring now to FIG. 13, the lower end of plastic tube 29 curves to horizontal direction and leads to the upper end of a short upright chute 30 in which a number of the cans 12 are stacked. The cans move downward gravitationally to a support 31 so dimensioned that the lowermost can is in alignment with a staking punch 46.

Referring now to FIG. 1, the apparatus comprises a split die 32, 34 which acts as a clamp to receive and hold a lead wire 16, this initially being the forward end of the endless wire entering at 16'. The wire 16' is fed through a guide bushing 36, and then through a small hardened bushing in a fixed shear plate 38, to the split die 32, 34. The short lead wire 16 is severed from the long wire 16' by movement of the split die in a direction laterally of the lead wire by suitable means, here indicated to be a cam 40 engaging a cam roller 42 carried by the split die. The dies 32 and 34 may be faced with hardened face plates 32' and 34', respectively.

The apparatus further comprises a punch 44 and means to reciprocate the same in the direction of the lead wire in order to upset or head the wire a short distance from its end. A second punch 46 serves to feed a can 12 in the direction of the lead wire to place the bottom hole of the can over the end of the wire as far as the head, and serves further to stake or rivet the end of the wire. The split die 32, 34 is then released, as by means of strike plates 48 on the sides of cam 40, which plates engage rods 50, the remote ends of which serve to move the die portion 32 away from die portion 34 in order to release and discharge the lead wire with the attached can downward gravitationally.

It will be understood that the cam 40 serves not only to sever the lead wire 16 from the continuous wire, but also to move the same to the heading station on the axis of punch 44, and next to the staking station on the axis of punch 46. Later the split die moves back to the cutting station on the axis of wire 16' to receive a new piece of wire to be severed.

The machine has a main shaft 52 which carries the cam 40 and strike plates 48. This shaft may be driven in any desired fashion, as by means of a motor (not shown in FIG. 1 but located at 49 in FIG. 12) connected to the shaft through a suitable belt or gearing or a chain indicated at 54 (FIG. 1). The chain housing is shown at 55 in FIG. 12. The heading punch 44 (FIG. 1) is carried by a slide 56 which is moved by a cam 58 engaging a cam roller 60 carried by the slide 56. The staking punch 46 is carried by a similar slide 62 which is moved by a cam 64 engaging a cam roller 66 on the slide 62. The cams 58 and 64 are carried by a shaft 68 which is driven in one-to-one ratio with the shaft 52, as by means of mitre gears 70, 72.

Considering the machine in greater detail, and referring next to FIG. 2, the halves 32 and 34 of the split die are cut away at their adjacent faces, as shown at 74 and 76, for precision engagement at the clamp surfaces 78. The hardened plates 32' and 34' (FIG. 1) are similarly shaped. The cam roller 42 (FIG. 2) is carried by die part 34, so that cam 40 moves die part 34 against part 32, and the latter is yieldably restrained by a compression spring 80 which acts also as a return spring. The compression spring is preferably positioned around a guide rod 82 having an end 84 secured in die 32. The other or remote end of rod 82 is freely slideable through a fixed block 86 which is secured to one end of a fixed bed or guide rail 88. This overlies the table 90 of the machine, it being located by dowels or pins 92, and secured by screws 94. The rail 88 acts as a guide surface on which the split die 32, 34 slides, and which also cooperates with side guides for the split die, these being shown at 38 and 98 in FIGS. 1 and 3. The shear plate and guide 38 may be secured to the side of a base block 100, which is fastened adjustably, as by means of slots 102 receiving screws 104. The slots make it possible to vary the lead wire length to fit the needs of the purchaser. If locating dowels are used, there are multiple dowel holes for a change in increments, say one-fourth inch increments.

Reverting to FIG. 2, the end of rod 82 is threaded and receives a pair of stop nuts 106 which are adjusted to limit the return movement of die 32. The adjustment is made such that die 34 can move slightly further toward cam 40, thereby loosening the clamp grip of the die, so that it more readily receives the end of the continuous wire as it is fed into the die. This release is further assured by the introduction of a small compression spring between the die portions, as shown at 108 in FIGS. 1 and 3.

The travel of the split die to the staking station may be accurately limited by the provision of an adjustable stop screw 110 (FIG. 2), threadedly received in a block 112, and locked by a lock nut 114. The block 112 is fixed on the bottom rail or bed 88, as by means of screws 116.

The two rods 50 pass freely through the die 34 and are secured to the die 32, as by means of set screws 118 (FIG. 2). The strike plates are not visible in FIG. 2 but are shown at 48 in FIG. 1 and also in FIG. 9. They are conveniently mounted on each side of the cam 40, as by means of screws 120. It will be evident from inspection of FIG. 9 that the maximum rise of the cam is at 122, this corresponding to the staking station previously referred to. Thereafter the die moves back slightly, as indicated by the reduction in cam radius at 124, and at this time the strike plates come into action and move die 32 slightly away from die 34, thereby releasing the lead wire and the cam secured thereto, so that they can drop gravitationally into a suitable box or bin beneath the table 90 of the machine.

The cam 40 rotates counterclockwise as viewed in FIG. 9, and the minimum radius portion 126 corresponds to the first station in which the die is aligned with the bushing and shear plate through which the wire is fed. The next part 128 of somewhat larger radius corresponds to the first punch station or heading station. The large radius part 122 moves the die to the second punch station or staking station. The part 124 corresponds to discharge of the finished product, as above described.

FIG. 3 shows how the split die is guided between shear plate 38 on one side, and guide 98 on the other side. Guide 98 is kept low in height in order not to interfere with the punches at the two punch stations. On both sides the guides also hold the die downward on rail 88, the bottom of the die being enlarged at 130 and 132 for this purpose. FIG. 3 also shows how shear plate 38 is secured to mounting block 100, the latter in turn being fastened on table 90 by means of screws 104. The latter are received in slots best shown at 102 in FIG. 1, as

was previously described. The adjustment is to change the lead wire length.

The heading punch station may be described with reference to FIGS. 4, 5 and 7. The punch 44 may be adjusted 5 longitudinally by means of a capstan head screw 140, the adjustment of which may be locked by means of a set screw 142 bearing on a softer metal plug 143, while the position of the punch 44 is additionally locked by means of a set screw 144. This bears on a flat on top of the punch. The slide 56 is cut away as shown at 146 to receive the screw 140. The rear end of the slide is bifurcated at 148 to receive the cam roller 60, and the bottom of the slide is channeled at 150 to house a compression return spring 152 which urges the slide rearwardly, with the roller 60 engaging the cam 58. The forward end of spring 152 bears against a fixed plate 154 secured by screws 156 to the end of a fixed rail 158 which is mounted on the table 90. The rear end of spring 152 bears against a movable plate 159 which is secured to 15 the slide, and which bridges the channel 150 and the 20 spring 152, the part 159 being secured by screws 160.

The slide 56 is guided between side rails 162 (FIG. 5) and by a top plate 164, the assembly being held on table 90 by means of long screws 166. FIGS. 1 and 4 show how 25 the rear portion of top plate 164 is cut away at 168 to clear the cam roller 60 and cam 58.

Referring to FIG. 7, the end of punch 44 is counterbored at 170 to receive the end of the lead wire 16 for a limited distance. The adjacent face of the split die has a 30 small recessed seat at 172. This shapes the head, and is preferably frustoconical in shape as shown. The initial projection of lead wire 16 is greater than the depth of the hole in the punch shown at 170, and the action of the 35 punch then is to upset the lead wire at the seat 172, thus forming a head which is spaced a short distance from the tip of the wire.

It is essential to lock the lead wire against axial movement during this heading operation. It will be recalled by reference to FIG. 2 that the split die 32, 34 normally is 40 closed under pressure of a compression spring 80. At the heading station the split die is additionally closed or locked by the provision of two wedge elements, one of which is shown at 176 in FIGS. 4 and 7, and both of 45 which may be seen in FIG. 1. The wedge elements 176 are carried by the forward end of slide 56, and they engage mating parts of the split die in order to clamp the said parts tightly together. In the present case the wedge elements are pointed or tapered dowels, and referring to FIG. 2 die portions 32 and 34 have mating holes 178. It will be 50 evident that these parts hold the split die closed positively, instead of yieldingly, during the heading operation.

Another thing which helps lock the lead wire 16 against 55 axial movement is the extension of the shear plate 38, and referring to FIG. 1 it will be seen that the shear plate is so long that the newly sheared rear end of the lead wire bears against the shear plate at each of the two punch stations. Because the body of the lead wire is additionally closely confined in the mating receptive grooves 60 of the split die and therefore cannot bend, the support by the shear plate 38 prevents axial movement.

FIG. 10 shows the cam 58 which operates the heading punch. The small radius part 180 corresponds to retraction of the punch, and the large radius part 182 corresponds to advance of the punch. It will be seen by comparison of FIGS. 9 and 10 that the punch is advanced and then partially retracted while cam 40 locates the split die at the first punch station. On retraction of the heading punch, cam 40 moves the split die further to staking station.

The cam which operates the staking punch is shown in FIG. 11. The cam rise at 184 follows (i.e. is timed later than) the beginning of the rise 122 of cam 40 which moves the split die to the staking station, and follows the rise 75 182 of cam 58, as it should.

The staking punch may be described with reference to FIG. 6, but with the understanding that FIGS. 4 and 5 are also applicable in that the slide 62 is the same as slide 56, it being guided on a bottom rail 158' like rail 158, and between side rails like rails 162, and beneath a top plate 164' like top plate 164, and having a bottom channel 150' housing a compression return spring 152', like the parts 150 and 152 previously described. However, the location in longitudinal direction of the assembly of slide and guides on the table 90 is somewhat different, these parts being located much nearer the cam shaft 68, as is clearly shown in FIG. 1. This is done in order to provide clearance for feed of the cans 12 to a position ahead of the retracted staking punch 46, and also because punch 46 is longer and has a longer stroke. The stepped relation of the slide assemblies shown in FIG. 1 accounts for the small diameter of the cam 64 (FIG. 11) compared to the large diameter of the cam 58 (FIG. 10).

Reverting to FIG. 6, the enlarged rear end 190 of the punch 46 is carried in slide 62 in the same manner as previously described for the heading punch 44, it being locked in position by a set screw 144', after axial adjustment by an adjusting screw 140', which itself may be locked by a set screw 142'. The top of part 190 preferably has a flat, and the lower end of screw 142' preferably bears on a softer metal plug. The forward part of the punch 46 is reduced in diameter to mate with the inside of the can being assembled by the machine.

The operation of the staking punch 46 may be described with reference to FIGS. 8 and 8A of the drawing. The end of punch 46 fits can 12 frictionally, and thus advances the can so as to place hole 14 over the tip of lead wire 16 all the way to the head 18. When the can reaches the head 18 it stops moving, and punch 46 continues its forward movement inside the can, as suggested by the broken line position 46'. It moves all the way to the bottom of the can at which time it rivets or expands or stakes the end of the lead wire, as shown at 20 in FIG. 8A. The shape of the expanded part 20 may be determined by a suitable recess 192 in the end of punch 46. The punch is then retracted as shown in FIG. 8A, the can 12 being held by the lead wire 16, which in turn is held by the grip of the split die. It will be understood that during the staking operation axial movement of lead wire 16 is prevented by the head 18, and by the shear plate 38 as previously described for the heading station.

As will be seen by comparison of cam 40 and cam 64 (FIGS. 9 and 11) retraction of the staking punch is followed by a slight return movement of the split die, thereby affording clearance from the stop screw 110 (FIGS. 1 and 2), whereupon the strike plates 48 (FIGS. 1 and 9) engage the push rods 50 (FIGS. 1 and 2), thus separating die 32 from die 34, and so releasing the assembled can and lead for gravity discharge downward through the opening 191 in table 90 to a box or bin therebeneath (not shown).

Reverting to FIG. 1, the shaft 52 is carried in suitable bearings 194 mounted on table 90. There are preferably three bearings, one on each side of cam 40 to support the same, and a third near the mitre gear 70. The shaft 68 is shorter and requires only two bearings 196, which similarly are mounted directly on the table 90.

If desired the discharge of the finished piece from the die may be accelerated by the provision of a suitable kicker, or by a downwardly directed air jet, or both. Also if desired, the feed of the cans to the staking punch may be modified by the addition of a shuttle for moving a can sidewardly to a position in front of the punch, instead of using the direct downward gravity feed shown in FIG. 13.

It is believed that the construction and operation of my improved machine for applying can leads to cans, as well as the advantages thereof, will be apparent from the foregoing detailed description. It will also be appar-

ent that while I have shown and described the apparatus in a preferred form, changes may be made without departing from the scope of the invention, as sought to be defined in the following claims.

We claim:

1. Apparatus for applying can leads to cans for electrical components, said cans having a small bottom hole to receive the lead wire, said apparatus comprising a split die acting as a clamp to receive and hold a lead wire, a punch and means to reciprocate the same in the direction of the lead wire to upset and head the wire a short distance from its end, a second punch to feed the can in the direction of the lead wire to place the bottom hole over the end of the wire as far as the head and to stake or rivet the end of the wire, and means to release the split die in order to discharge the lead wire with the attached can.

2. Apparatus as defined in claim 1, in which the lead wire is fed from a reel of continuous wire, and in which there is a shear plate and a feed means to feed wire from the reel through the shear plate into the split die, and in which there is a means to relatively move the split die and shear plate in a direction lateral to the lead wire in order to sever a desired length of lead wire from the continuous wire.

3. Apparatus as defined in claim 1, in which the lead wire is fed from a reel of continuous wire, and in which there is a fixed shear plate and a feed means to feed wire from the reel through the fixed shear plate into the split die, and in which there is a means to move the split die in a direction lateral to the lead wire in order to sever a desired length of lead wire from the continuous wire.

4. Apparatus as defined in claim 3, in which there is a cut off station, a first punch station displaced from the cut off station for heading the lead wire, and a second punch station displaced from the first punch station for staking the can on the lead wire, and in which the means to sever the lead wire shifts the split clamp from the cut off station to the first punch station and then to the second punch station.

5. Apparatus as defined in claim 3, in which there is a cut off station, a first punch station displaced from the cut off station for heading the lead wire, and a second punch station displaced from the first punch station for staking the can on the lead wire, and in which the means to sever the lead wire shifts the split clamp from the cut off station to the first punch station and then to the second punch station, and in which the shear plate is long enough to abut and support the rear end of the lead wire during the heading and staking operations at the forward end.

6. Apparatus as defined in claim 5, in which one end of the lead wire projects from the split die, and in which the face of the split die at the projecting end has a recessed seat to help form the upset head near the end of the lead wire.

7. Apparatus as defined in claim 6, in which the punch for upsetting a head on the lead wire is carried by and projects from the end of a slide, and in which the said end of the slide also has a pair of wedge elements which so engage mating parts of the split die as to clamp the parts of the split die tightly together during the heading operation.

8. Apparatus as defined in claim 7, in which the staking punch is received inside the can and advances the can to the head on the lead wire, and stakes or rivets the end of the lead wire inside the can.

9. Apparatus as defined in claim 7, in which the staking punch fits the inside of the can frictionally and first advances the can to and against the head on the lead wire, and only thereafter moves relative to the can to stake or rivet the end of the lead wire inside the can.

10. Apparatus as defined in claim 1, in which one end of the lead wire projects from the split die, and in which the face of the split die at the projecting end has a

recessed seat to help form the upset head near the end of the lead wire.

11. Apparatus as defined in claim 1, in which the punch for upsetting a head on the lead wire is carried by and projects from the end of a slide, and in which the said end of the slide also has a pair of wedge elements which so engage mating parts of the split die as to clamp the parts of the split die tightly together during the heading operation.

12. Apparatus as defined in claim 1, in which the staking punch fits the inside of the can frictionally and first advances the can to and against the head on the lead wire, and only thereafter moves relative to the can to stake or rivet the end of the lead wire inside the can.

13. Apparatus as defined in claim 1, in which the punch for upsetting a head on the lead wire is carried by and projects from the end of a slide, and in which the said end of the slide also has a pair of wedge elements which

so engage mating parts of the split die as to clamp the parts of the split die tightly together during the heading operation, and in which the staking punch fits the inside of the can frictionally and advances the can to and against the head on the lead wire, and only thereafter moves relative to the can to stake or rivet the end of the lead wire inside the can.
